Primary Examiner—Doris Clark

(74) Attorney, Agent, or Firm—Wood, Phillips, VanSanten,
Clark & Mortimer(57) **CLAIM**

The ornamental design for lawn edging panel, as shown and described.

DESCRIPTION

FIG. 1 is a top, side, and end perspective view of my design for lawn edging panel;

FIG. 2 is an elevation view thereof from the same side as in FIG. 1;

FIG. 3 is an elevation view thereof from the side opposite that in FIG. 2;

FIG. 4 is an elevation view thereof from the end of FIG. 1;

FIG. 5 is an elevation view thereof from the end opposite that in FIG. 4;

FIG. 6 is a top view thereof; and,

FIG. 7 is a bottom view thereof.

The portions of the drawings shown in dotted lines do not form a part of the claimed design.
